ATTORNEY

UNITED STATES PATENT OFFICE

MERLIN T. R. MAYNARD, OF SAN JOSE, CALIFORNIA

CORK

Application filed August 26, 1929. Serial No. 388,482.

This invention relates particularly to bottle corks made of rubber or any other suitably resilient material.

It is the object of the invention to provide a cork that not only functions as a seal to the bottle, but that also may be used for applying the liquid contents of the bottle to the scalp in desired quantities, and also as a scalp massaging device.

10 It is also an object of the invention to provide a device of the character indicated in which the massaging fingers or elements are so formed and disposed as to progressively increase the area of working surfaces as pressure is applied, and to present flat working areas to the scalp when in a working position.

15 It is still a further object of the invention to provide a device of the character indicated that effectually seals the bottle in which it is fitted and when not in use as an applicator, but which automatically opens to permit the discharge of liquid from the bottle when it is applied to the scalp.

20 25 In the drawings:

Figure 1 is a side elevation of a cork embodying my invention.

Figure 2 is a plan view of the same.

25 30 Figure 3 is a side elevation of the upper portion of the cork with one finger removed.

In the embodiment of the invention herein disclosed I show a molded cork having four upstanding fingers formed thereon, each finger having the following characteristics. 35 Its outer face is continuous with the outer surface of the cork as shown at 3, the reference 1 indicating the cork and 2 the finger. In the present case the finger occupies one-eighth of the end surface of the cork at its base, the sides sloping upwardly as at 4 to the flat end 5, and the inner side sloping upwardly and outwardly from a flat central portion 6 as at 7.

The end surface of the cork between each 45 two fingers slopes slightly downwardly and outwardly from the flat central portion 6 as indicated at 8.

A passage 9 is formed through the center of the cork, open at its lower end 10 but having its wall converge at the upper end as indi-

cated at 11 in such a manner as to be normally closed at this point.

The molded cork is cut downwardly a distance as to 12 in radial planes coinciding with its axis to lengthen the fingers 2 and form additional and shorter fingers 13, and to permit the opening of the upper end of passage 9 when the device is in use.

When the device is applied to the head and pressure applied thereto, the fingers 2 first 60 bend outwardly so that their faces 7 are brought to bear against the scalp. This spreading movement of the fingers separates them at the center of the cork and consequently opens the passage 9 and permits the liquid to flow out upon the scalp during the massaging movements. If the pressure is increased sufficiently to bring the fingers 13 into contact with the scalp, these are also bent outwardly, thereby opening the passage 70 wider and bringing their flexible inner points into play.

By means of the construction above set forth the liquid is released when desired and in the quantity desired, and the scalp is subjected to the massaging of the broad, flat surfaces 7 of fingers 2, and also to the narrow and more flexible finger tips of fingers 13.

In making this device I first mold the cork with the projecting fingers 2 thereon and the passage 9 therein, the said passage being closed at its forward end. Then by merely cutting the cork end as at 14 the fingers 2 are made longer, the short fingers 13 are formed, and the closed end of the passage 9 is cut 80 through to permit the release of liquid as described.

The smaller Figure 4 is introduced to show that the passage 9 may be made open at both ends, the open upper end being indicated at 90 15 without altering the construction of the fingers.

It is to be understood, of course, that while I have herein shown and described but one specific embodiment of the invention, changes in form, construction, and method of operation may be made within the scope of the appended claims.

I claim:

1. A cork having an axially disposed pas-

100

sage formed therein open at the inner end and normally closed at its outer end, the said outer end having a plurality of radially disposed fingers of resilient, flexible material formed thereon, the several fingers having engaging portions adapted to normally form a closure for the closed end of the passage.

2. A cork having a plurality of radially arranged and alternately disposed long and short fingers of resilient, flexible material formed on its outer end, the long fingers having blunt ends and sides sloping to its base portion both laterally and inwardly, the outer sides of all the fingers being continuous with the outer surface of the cork, the shorter fingers substantially duplicating the base portions of the long fingers, the said cork also having an axially disposed passage formed therein normally closed at one end by converging portions of the several fingers.

MERLIN T.-R. MAYNARD.
